(57) **ABSTRACT**

A new *verbena* plant particularly distinguished by orange
flowers with dark red centers, an upright growth habit, and
very good resistance to powdery mildew, disclosed.

1

Genus and species: *Verbena* sp.
Variety denomination: 'KLEVP15474'.

BACKGROUND OF THE NEW PLANT

The present invention comprises a new and distinct variety of *verbena*, botanically known as *Verbena* sp., and hereinafter referred to by the variety name 'KLEVP15474'. 'KLEVP15474' originated from a cross-pollination conducted in September 2010 in Cobbitty, New South Wales, Australia between the proprietary female *verbena* variety 'VC10 0021' (unpatented), and the proprietary male *verbena* variety 'VC10 0023' (unpatented).

The seeds from the cross were sown and plants were grown for evaluation, where an individual plant designated 'KLEVP15474' was selected from the group of plants in Cobbitty, New South Wales, Australia in April 2011.

In April 2011, 'KLEVP15474' was first vegetatively propagated by vegetative cuttings in Cobbitty, NSW, Australia. 'KLEVP15474' was found to reproduce true to type in successive generations of asexual propagation via vegetative stem cuttings.

SUMMARY

The following are the most outstanding and distinguishing characteristics of this new variety when grown under normal horticultural practices in Cobbitty, New South Wales, Australia.

1. Orange flowers with a dark red center;
2. An upright growth habit; and
3. Very good resistance to powdery mildew.

DESCRIPTION OF THE PHOTOGRAPH

This new *verbena* plant is illustrated by the accompanying photograph which shows the plant's overall plant habit including form, foliage, and flowers. The photograph is of a 13-week-old plant grown in a greenhouse in Stuttgart,

2

Germany in May, 2014. The colors shown are as true as can be reasonably obtained by conventional photographic procedures.

5 DESCRIPTION OF THE NEW VARIETY

The following detailed descriptions set forth the distinctive characteristics of 'KLEVP15474'. The data which define these characteristics were collected from asexual reproductions carried out in Cobbitty, New South Wales, Australia. Data was collected on three-month-old plants grown in a greenhouse in Cobbitty, New South Wales, Australia in February 2015 in Cobbitty, New South Wales, Australia. Color references are to The R.H.S. Colour Chart of The Royal Horticultural Society of London (R.H.S.), 5th edition (2007).

Classification:

Family.—Verbenaceae.

Botanical.—*Verbena* sp.

Common.—*Verbena*.

Designation.—'KLEVP15474'.

Parentage:

Female parent.—The proprietary female *verbena* variety 'VC10 0021' (unpatented).

Male parent.—The proprietary male *verbena* variety 'VC10 0023' (unpatented).

Plant:

Growth and branching habit.—Upright.

Height (from top of soil).—30.0 cm.

Width (horizontal plant diameter).—30.0 cm

Time to produce a finished flowering plant.—Approximately 8 weeks.

Time to initiate and develop roots.—3 weeks.

Root description.—White, RHS155B, Fine fibrous roots.

Stems:

Number of branches per plant.—More than 35.

Length.—20.0 cm.

Diameter.—1.0 cm.

Internode length.—Approximately 2.0 cm.
